UNITED STATES PATENT OFFICE

SAMUEL J. OLIVER, OF EAST ORANGE, NEW JERSEY

DESIGN FOR UPHOLSTERY AND DRAPERY FABRIC

Application filed August 22, 1932. Serial No. 44,663. Term of patent 3½ years.

To all whom it may concern:

Be it known that I, SAMUEL J. OLIVER, a citizen of the United States of America, residing at East Orange, Essex County, State of New Jersey, have invented a new, original, and ornamental Design for Upholstery and Drapery Fabric, of which the following is a specification, reference being had to the accompanying drawing, forming part thereof, and in which the diagonal cross hatch lines in the several blocked areas represent different colors, similar cross hatching representing the same color.

The figure is a plan view of a fragmentary portion of a fabric showing my new design.

I claim:—

The ornamental design for upholstery and drapery fabric, as shown and described.

SAMUEL J. OLIVER.
